[57] CLAIM

The ornamental design for a bicycle tire tread, as shown
and described.

DESCRIPTION

FIG. 1 is a perspective view of a bicycle tire tread showing my new design, it being understood that the pattern is repeated uniformly throughout the circumference of the tread as shown schematically in solid lines; FIG. 2 is an enlarged fragmentary plan view showing the tread pattern in greater detail;

FIG. 3 is an enlarged fragmentary side elevation view thereof; and

FIG. 4 is a transverse section view taken substantially along the line 4—4 of FIG. 3 illustrating the profile of the tire tread in greater detail.

The broken lines in the drawing are for illustrative purposes only and form no part of the claimed design.
